MOP SWAB AND HEAD

Leslie M. Thornton, Kansas City, Mo.

Application September 20, 1930
Serial No. 483,222

10 Claims. (Cl. 15—229)

My invention relates to mop swabs and heads, and more particularly to a double faced reversible mop swab and a mop head for pivotally supporting the same on a handle.

5 It is a purpose of my invention to provide a mop swab that can be readily assembled with a mop head, and more particularly with a reversible mop head made of wire or similar material that is so constructed that the same may be moved into a plurality of angular positions relative to the handle of the mop and will remain in adjusted angular position, the handle of the mop passing through an opening in the swab to permit the same to assume the different angular positions thereof.

10 It is a further purpose of my invention to provide a mop swab and mop head that are so shaped and are of such relative proportions that the mop swab will not be accidentally disassembled from the mop head, although the same may be readily put into position and readily removed from the head of the mop by contraction of the mop head to either assemble or disassemble the swab and head.

15 It is a further purpose of my invention to provide a mop swab that is provided with a body portion of fabric that is so shaped that the mop will readily enter corners and recesses, such as exist in the walls of rooms under ordinary circumstances, and which at the same time is so shaped that there will be a minimum waste of material in cutting out the blanks or sections of cloth from which the mop swab is made. In order to do this the sections of the mop swab body portion of fabric are made of a triangular form with a rounded forward end portion and a substantially straight rear edge portion, except for a recess or slot provided therein, the sections being of generally triangular form with the widest portion thereof closely adjacent the rear edge thereof, and with the side edges of the same straight or substantially straight. The maximum over all length of the body portion of the mop swab is preferably greater than the maximum width or transverse diameter of said body portion.

20 It is a further purpose of my invention to provide a mop swab that has the yarn secured to and extending from both faces thereof, said yarn being preferably secured to each of the two sections of fabric forming the body portion of the swab by continuous stitching to thus simplify the application of the yarn to the body portion, and in order to assure the firm securing of said yarn to said fabric it is first stitched down by one continuous seam, and then is

stitched down a second time by a seam running substantially parallel to the first seam and closely adjacent thereto.

25 It is a further purpose of my invention to provide a mop swab that is so constructed and provided with a slot or opening of such size and proportions in the large or rear end portion thereof, that the mop head can be passed through said slot into the pocket formed in the body portion, upon transverse contraction of said head portion, and the opposite rear corners of said frame or head portion can be readily engaged with the corresponding portions of the pocket through the openings provided in said pocket along the edges of said slot or recess in the body portion.

30 Other objects and advantages of my invention will appear as the description of the drawing proceeds. I desire to have it understood, however, that I do not intend to limit myself to the details of structure shown or described, except as defined by the claims.

35 In the drawing:

Fig. 1 is a sectional view through the mop swab taken substantially on a plane corresponding to that of the mop head, the mop head being shown in elevation, and being shown in normal condition.

40 Fig. 2 is a fragmentary sectional view similar to Fig. 1, showing the frame in contracted position, and the body portion expanded transversely at the wide slotted end thereof to permit assembly of the same with the mop head.

45 Fig. 3 is a perspective view looking downwardly at an oblique angle at the mop swab and head, showing the mop head being moved into position to be assembled with the mop swab.

50 Fig. 4 is a perspective view partly broken away, showing the two halves of the body portion of the mop partly sewed together.

55 Fig. 5 is a section taken on the line 5—5 of Fig. 1.

60 Fig. 6 is a perspective view of one of the mop swab body fabric sections or blanks, and

65 Fig. 7 is a diagrammatic view of a piece of fabric showing the manner in which the fabric mop swab body sections or blanks are cut therefrom.

70 Referring in detail to the drawing, my improved mop swab is made to be used with a triangular mop head or frame that is so constructed that the same may be contracted at the wide rear end thereof to reduce the transverse diameter of said head or frame. The frame is preferably made of wire, and as will be clear from Figs. 110

1, 2 and 3, said frame is preferably provided with a rounded or curved forward end portion 10, the straight side members 11 diverging from the curved end 10 to the rear portion of said frame, 5 which is the widest part thereof.

At the rear end of the frame the side members are turned inwardly to form the rear cross members 12, which extend toward each other, and the portions 13 that extend at an oblique angle to 10 the portions 12 to a point adjacent the center of the side members 11, but preferably slightly to the rear of the center thereof, where said portions 13 of the frame are welded or otherwise secured at 14 to the straight side members 11. 15 From this point the aligned pivot members 15 extend inwardly and through the bearing members 16, made in the form of sleeves, on the clip 17. The inner ends 18 of said pivot members 15, are turned substantially at right angles to the members 15 and are normally in engagement with 20 the inner opposed end faces of the tubular or sleeve-like bearing members 16, being held in such engagement by the resiliency of the frame, which is made of spring wire, and engaging said inner ends of said tubular members 16 with sufficient friction to hold the mop frame or head in any desired angular position relative to the 25 handle 19, which carries the clip 17.

The pivot members 15 are longitudinally slideable in the tubular or sleeve-like members 16 to 30 permit contraction of the frame transversely thereof to reduce the width thereof at the point of maximum transverse width of the same, or at the rear end portion thereof. The cross members 12 are of such length as to leave a relatively 35 large amount of space between the inner ends thereof at the point where the portions 13 of the frame join therewith, to permit such transverse contraction of the frame as may be desired, the 40 contraction of said frame being limited only by the engagement of the laterally bent ends 18 of the members 15 with each other.

The relative size of the opening between said 45 members 12 at the rear end of the mop head and the wire clip supporting means 20, is such that the clip supporting means can always be swung freely through said opening. The triangular portions provided in the frame rearwardly of the pivot members 15 comprising the rear transverse 50 portions 12, the obliquely extending portions 13, and part of the side members 11, provide a pair of spaced heel portions triangular in shape at the rear of the frame or head.

The mop swab cooperating with said head or 55 frame is made of such a size and shape that the same will snugly fit about the frame, as shown in Fig. 1, when the frame is in normal position with the laterally projecting portions 18 in frictional engagement with the inner ends of the tubular or 60 sleeve-like members 16 on the clip 17. The mop swab is, however, made slightly larger than the frame in the factory, as a slight amount of shrinkage will occur in laundering and this is allowed for so that the relative proportion of the parts 65 shown in Fig. 1 will exist after the mop swab has been washed, as otherwise the mop swab might contract the frame when placed in position thereon causing the members 18 to be moved out of frictional engagement with the rear end 70 of the sleeve-like members 16, and interfering with the frictional action between these parts, which causes the frame to be held in any adjusted position relative to the handle. While the swab is provided with a pocket in the body portion thereof, that is of such a size after washing the

swab that the same will be substantially smooth and extended when the same is in position on the frame, it will not be stretched by the frame to the extent that it will prevent the laterally directed end members 18 on the frame from serving their purpose.

The body portion of the swab comprises a pair of fabric sections 21, which are generally triangular in shape, having the rounded forward end portions 22 and the straight side portions 23, diverging continuously from said rounded forward end portions 22 to the rear end portions of said members. The rear end portions of the members 21 have the slots 24 therein, that define the heel portions 25 that are spaced from each other, and which have the substantially straight rear edges 26 aligning with each other, and joined with the straight side edges 23 of the members 21, by the slightly rounded corners 27. The side edges 28 of the slots are curved slightly to provide a relatively narrow entrance to the slots and a wider portion at the inner ends of the slots 24 which have the curved edges 29 joining the edges 28, said slots extending inwardly from the rear edges of the sections 21 substantially on the longitudinal center line of the same.

The triangular shape of the blanks or fabric sections 21, two or which form the body portion of the mop swab, is particularly advantageous in 105 connection with the cost of the mop swabs, as it results in a great saving of material over any other feasible shape of mop swab body portion, this being obvious from Fig. 7, in which a sheet of fabric 30, is shown. By cutting the fabric 110 members 21 from the material so that the same are cut therefrom in alternating arrangement, as will be evident from Fig. 6, that is, with one thereof cut from the fabric so that the rounded end 22 is adjacent the one side edge 31 of the 115 fabric, and the adjoining ones with the rear edges 26 aligning with the edge 31 of the fabric there is but very little waste, there being only two small substantially triangular pieces of fabric 32, wasted between the adjoining ends of the fabric 120 members and the portions 24' that are cut out to form the slots 24. In other words, there are two of the pieces 32 and the one piece 24' wasted for each of the members 21, and that is all.

The over all length of each of the members 21 125 from the extremity of the rounded end 22 to a line connecting the rear edge portions 26 thereof, is somewhat greater than the greatest transverse dimension of the member 21, which is that dimension from the point where the curved edge 27 130 meets the straight edge 23, on one side of said member 21 to the corresponding point on the other side thereof, or very closely adjacent the extreme rear edge 26 of the same. This provides an elongated triangular shape for the body portion of the mop swab when it is completed, or in other words, one in which the straight sides 23 are extended at an angle of less than 60 degrees to each other, as would be the case if the body portion formed an equilateral triangle.

In making the mop swab two of the blanks 21 are used. Each blank 21 has yarn or thread 33 provided thereon on one face thereof, so as to make a double faced mop swab when the same is completed. The yarn or thread 33 is secured to the fabric members 21 by means of stitching. The strands of the yarn or thread are placed in as nearly parallel position as these can be placed in engagement with that surface of the member 21, which will form the outer face thereof, and 145 150

are stitched to the member 21, suitable lines 54 being preferably printed on the members 21 to aid the operator in sewing the yarn thereto at the proper place.

5 The stitching is begun at the point 34, and a continuous seam is run around the member 21 from the point 34, following the path shown in the drawing first extending diagonally, as shown at 35, to a point opposite the rounded end 29, 10 of the slot 24, then substantially parallel to the center line of the slot, but spaced from the edge 28 thereof, as shown clearly in Fig. 4, to a point 36 spaced from the rear edge 26 of the blank 21, then parallel to said rear edge 26, the curved 15 corner 27, the straight side edge 23, the rounded forward end 22, and the other straight side edge 23 at substantially the same distance from all said edges, then substantially parallel to the opposite rounded corner 27 at the rear of the member 21, and substantially parallel to the rear edge 26 of the opposite heel portion 25 until the point 36 is reached on the opposite side of the slot 24, then parallel to the center line of said slot 24 until a point opposite the rounded end 29 of said 20 slot 24 is reached, and from that point diagonally, as indicated at 35', back to the point of beginning at 34.

After the yarn has been stitched down in this manner by one seam, the same is firmly secured 30 to the member 21, but some of the strands thereof may not have been caught by the seam. In order to assure that all the threads are firmly anchored, the yarn is stitched down a second time by a seam running substantially parallel to, and 35 very closely adjacent the first seam, as will be evident from Fig. 4, and inasmuch as the first seam was a continuous one, this can be readily and very quickly done by merely straightening out the strands of yarn and again running the 40 member 21 with the yarn thereon through the sewing machine, following the first seam in doing so.

There is a great advantage obtained by having a continuous seam for holding the yarn in 45 position, such continuous seam saving much unnecessary sewing, such as would be the case where the yarn is not arranged in such a continuous manner. This is possible due to the shape of the mop swab, and due to the fact that the stitching 50 that forms the means of securement for the yarn, and thus determines the arrangement of the yarn on the swab comprises an inner substantially V-shaped portion, and an outer substantially U-shaped portion connected by the transverse portions parallel to the rear edges 26 of the mop 55 21. A binding 37 of tape is stitched around the edges 28 and 29 of each of the slots 24 to strengthen and prevent ravelling of the fabric. When the tape 37 is sewed to the edges 28 and 29 the same 60 tends to slightly distort the fabric throwing the adjacent sides of the heel portions on opposite sides of the entrance to the slot slightly away from each other. This causes a widening of the slot at the entrance thereto and causes the edges 65 28 to assume more nearly a parallel relation to each other than before applying the binding.

To complete the mop swab, two of the fabric sections 21 are placed in face to face relationship 70 with the yarn outward, and the sections 21 are secured together by means of a tape binding 38, which passes around the edges 22, 23, 27 and 26 of the members 21, and is stitched thereto. The tape 38 extends only to the corner where the rear edge 26 meets the edge 28, at each side of the 75 slot 24, said tape 38 overlapping the tape 37. A

row of diagonal stitches 40 is provided at each of the corners of the heel portions of the swab adjacent the slot 24, which forms a very small pocket in said corner to receive the slightly rounded corner 41 of the frame at the junction of the 80 portions 12 and 13 thereof.

This will prevent accidental disengagement of the mop head and swab when the head is in its normal or extended condition. Furthermore, the 85 distance from the point where the diagonal stitching 40 meets the edge 28 on each side of the swab to the extreme forward end portion of the rounded forward end 22, is less than the distance from the corner 42 of the frame to the point 43 on the opposite side of the frame, where the curved forward end 10 of the frame meets the straight side 11 thereof, when said frame is in normal condition.

In assembling the mop swab with the head or frame the rear portion of the swab is stretched transversely, which is possible due to the provision of the slot 24, to separate the heel portions 25 thereof as much as possible, and the frame is contracted transversely in the manner shown in Fig. 3, the frame being moved longitudinally toward the opening 44 that exists between the edges 28 and the edges 29 at the slot 24, the forward rounded end 10 of the frame being passed longitudinally into the pocket in the swab in the same manner that a handle is inserted in a glove, this being continued until the rounded end 10 of the frame is in engagement with the rounded end 22 of the swab, at which time the corners 42 of the frame will lie adjacent the ends of the opening 44 at the point where the stitching 40 meets the edges 28.

The rear portion of the swab is stretched transversely at this time, as indicated in Fig. 2, the ordinarily approximately parallel edges 28 of the slot 24 extending at an oblique angle in diverging relation, as shown in Fig. 2, and the heel portions 25 being pulled laterally outwardly, as shown in Fig. 2. The swab and frame are made of such relative size that the swab, after shrinkage, due to washing, will be of sufficient size that the heel portions of the swab will pass over the corners 42 by pulling slightly on said heel portions in a direction lengthwise of the side members 11 of the frame, the fabric then being stretched substantially to its limit from the point where the stitching 40 meets the edge 28 on one side of the opening or slot 24, to the point 43 on the opposite side of the frame, where bending of the member 11 takes place as the frame is contracted crosswise.

After the corner 42 has been passed by the inner edge of the heel portions on opposite sides of the slot 24, the swab can be readily moved into position onto the frame by pushing the heel portions thereof toward each other on the heel portions of the frame. With the frame in normal position the distance from the corner 42 to the point 43 on the opposite side of the frame is greater than the distance from the point where the stitching 40 meets the edge 28 on the corresponding heel portion of the swab to the extreme forward end portion 22 of said swab, which makes it impossible for the swab to accidentally come off the head or frame of the mop. This is one of the reasons for making the frame of a triangular shape with the straight sides 11 and the swab of a corresponding shape with the straight sides 23, and slightly elongated rather than of an equilateral form.

The tape binding 38 serves not only to firmly secure the members 21 together, but also serves

to prevent the ravelling of the edges of the fabric members 21, which are cut on the bias, and furthermore prevents the wire frame from coming into contact with the furniture or woodwork in 5 using the mop, as it provides a thick doubled edge portion around the frame.

Having thus described my invention what I claim is:—

1. In a mop swab, a body portion comprising a 10 pair of fabric members, each of said fabric members tapering from a wide rear end portion to a narrow rounded forward end portion and each having an elongated narrow slot extending substantially centrally from the rear edge thereof 15 toward said forward end, said fabric members being secured together adjacent the peripheral edges thereof from the rear end thereof to said forward end and having the entire rear edges thereof on opposite sides of said slot secured together, said slot defining a pair of wide, elongated, 20 spaced heel portions on each of said members, the edges of each of said members defining said slots being free to provide a slit in said body portion opening into the pocket formed by said members.
2. In a mop swab, a body portion comprising a 25 pair of duplicate fabric members, each of said fabric members tapering from a wide rear end portion to a narrow rounded forward end portion and each having an elongated narrow slot extending substantially centrally from the rear edge thereof toward said forward end, said fabric members being secured together adjacent the peripheral edges thereof from the rear end thereof to said forward end and having the entire rear edges thereof on opposite sides of said slot secured together, the edges of each of said members defining said slots being free to provide a slit in said body portion opening into the pocket formed by said members, said slot extending to 30 adjacent the center of said body portion to define a pair of spaced, wide, elongated separable heel pocket portions lying slightly to the rear of said center on opposite sides of the longitudinal center line of said body portion and a triangular pocket portion of substantially fixed width forwardly of said slot, said heel pockets being open to said triangular pocket and to said slot, but being otherwise closed.
3. In a mop swab, a body portion comprising a 35 pair of fabric members, each of said fabric members having a narrow rounded forward end portion and a wide rear end portion and each having a longitudinal slot extending inwardly from the central portion of the rear end thereof, said slot defining heel portions on opposite sides thereof, said members having all the peripheral edges thereof stitched together except the edges forming said slot, the edges of said members defining said slot being left free except adjacent the rear corners of said heel portions adjacent said slot and stitching extending diagonally across said corners securing together said corners of said heel portions.
4. In a mop swab, a body portion comprising a 40 pair of fabric members, each of said fabric members tapering from a wide rear end portion to a narrow rounded forward end portion and each having an elongated narrow slot extending substantially centrally from the rear edge thereof toward said forward end, a binding strip secured around the edges of each of said slots, said fabric members being secured together adjacent the peripheral edges thereof from the rear end thereof to said forward end and having the entire rear

transverse edges thereof on opposite sides of said slot secured together to completely close the same, said slot defining a pair of elongated spaced heel portions on each of said members gradually widening toward the rear edges thereof, the edges of each of said members defining said slots being free to provide a slit in said body portion opening into the pocket formed by said members.

5. In a mop swab, a body portion comprising a 45 pair of fabric members, each of said fabric members having a narrow rounded forward end and gradually widening rearwardly therefrom, and each having a longitudinal slot extending inwardly from the central portion of the rear end thereof, said slot extending inwardly to adjacent the center of each of said members and defining elongated heel portions wider than said slot on opposite sides thereof, said members having all the peripheral edges thereof stitched together except the edges forming said slot.

6. In a mop swab, a body portion adapted to receive a mop head comprising a pair of duplicate fabric members having each a pair of straight side edges converging toward a rounded forward end portion, said fabric members being secured together by stitching along said side edges and said forward end portion to form a pocket between said fabric members of a generally triangular shape, said fabric members each having substantially straight rear edges extending inwardly toward each other from said straight side edges and terminating in spaced relation to provide a slot in said body portion extending inwardly from the rear edge thereof toward the center of said body portion and defining a pair of spaced heel portions at the rear end of said body portion, the rear edges of said fabric members being joined together by stitching, but being left free along the side edges and inner edge of said slot to provide means for slipping a mop 100 head into the pocket formed between said fabric members, and yarn stitched to each of said fabric members by a continuous seam extending substantially parallel to the side and rear edges of said body portion and to the sides of said slot.

7. The combination with a resilient triangular mop head having a pair of spaced heel portions at the rear side thereof movable toward each other to reduce the maximum transverse dimension thereof and defining a central opening between the same, of a triangular mop swab comprising a body portion having substantially the same length and maximum transverse dimension as said frame when in normal position, and having a portion thereof cut away at the rear wide end thereof to provide a slot extending inwardly from the rear edge of said body portion, and defining a pair of spaced heel portions having closed rear edges, said body portion forming a pocket open around the edges of said slot, whereby said heel portions are movable transversely away from each other to pass said mop head in contracted condition through said slot and into said pocket, and said heel portions of said frame into interlocking engagement with the heel portions of said swab, the heel portions of said frame being completely enclosed within the heel portions of said swab.

8. In a mop swab, a body portion adapted to receive a mop head comprising a pair of duplicate fabric members having each a pair of straight side edges converging toward a rounded forward end portion, said fabric members being secured together by stitching along said side edges and said forward end portion to form a 145

- 5 pocket between said fabric members of a generally triangular shape, said fabric members each having substantially straight rear edges extending inwardly toward each other from said straight side edges and terminating in spaced relation to provide a slot in said body portion extending inwardly from the rear edge thereof toward the center of said body portion and defining a pair of spaced heel portions at the rear 80
- 10 end of said body portion, the rear edges of said fabric members being joined together by stitching, but being left free along the side edges and inner edge of said slot to provide means for slipping a mop head into the pocket formed between 85
- 15 said fabric members, and yarn stitched to each of said fabric members by a continuous seam extending substantially parallel to the side and rear edges of said body portion and to the sides of said slot, and forming an outer U-shaped band 90
- 20 of yarn and an inner V-shaped band of yarn joined at the rear of said heel portions. 95
9. The combination with a triangular mop head having a rounded forward end portion and having its greatest width at the rear end thereof, said rear end comprising a pair of spaced forwardly tapering, elongated, heel portions movable toward each other to transversely contract said head at its portion of greatest width, of a triangular mop swab having a body portion 100
- 30 provided with a rounded forward end portion and being of greatest width at the rear end thereof, the length of said head and swab body portion and the width of said head and swab body portion being substantially the same in normal undistorted condition, said body portion 105
- 35 having an elongated slot extending inwardly from the rear edge thereof to define a pair of forwardly tapering elongated heel portions, said body portion forming a pocket open only at the edges 110
- 40 of said slot, said heel portions of said swab being movable transversely away from each other on opposite sides of said slot to increase the maximum width of said body portion to enable the extremities of the heel portions of said frame while 115

- contracted to be passed between the edges of said slot adjacent the rear edge of said body portion and into the heel portions of said pocket with the forward rounded end of said frame seated in the forward rounded end of said pocket, and the rear transverse members of the heel portions of said head in engagement throughout their width with the closed rear edges of said heel portions of said swab.
10. In a mop, a contractible resilient triangular frame having spaced heel portions terminating in inwardly extending end portions forwardly of the rear edge thereof normally spaced from each other to provide an opening in said frame between said heel portions, a triangular reversible mop swab having a pocket therein for receiving said frame and having a slot extending inwardly from the rear edge thereof, having the edges thereof free to provide an opening to said pocket narrower than said frame in normal position, but wider than said frame in contracted position to permit assembly of said mop swab on said frame, and a clip having means thereon for attaching the same to a handle, said clip having axially spaced bearing members thereon pivotally receiving the inwardly extending end portions of said frame and cooperating means on said spaced bearing members and said inwardly extending end portions to transversely tension said resilient frame whereby said cooperating means are frictionally held in engagement by the resilient action of said frame, said end portions being spaced apart a distance such as to permit transverse contraction of said frame so that said mop swab may be slipped thereon by a longitudinal movement thereof relative to said frame, said slot providing an opening for the passage of said clip therethrough upon reversal of said mop, and said swab being of such transverse dimensions with relation to said frame as to be adapted to expand transversely beyond the limit of transverse expansion of said frame with the ends of said frame engaging said clip. 105
